(57) **CLAIM**

The ornamental design for a multi-port catheter assembly for a respiratory care system, as shown and described herein.

DESCRIPTION

FIG. 1 is a perspective view of a multi-port catheter assembly for a respiratory care system showing our new design; FIG. 2 is a left side elevational view thereof;

FIG. 3 is a top plan view thereof;

FIG. 4 is a right side elevational view thereof; and,

FIG. 5 is a bottom plan view thereof.

The broken line showing in FIGS. 1 through 5 are for illustrative purposes only and forms no part of the claimed design.
